DESIGN FOR A COMB HOLDER

Herbert E. Dahlen, Portland, Oreg.

Application April 3, 1947, Serial No. 138,137

Term of patent 3½ years

(Cl. D86—10)

To all whom it may concern:

Be it known that I, Herbert E. Dahlen, a citizen of the United States, residing at Portland, in the county of Multnomah and State of Oregon, have invented a new, original, and ornamental Design for a Comb Holder, of which the following is a specification, reference being had to the accompanying drawing, forming part thereof.

Fig. 1 is a front perspective view of a comb holder, showing my new design.

Fig. 2 is a side elevational view of the comb holder shown in Fig. 1.

I claim:

The ornamental design for a comb holder, as shown.
